UNITED STATES PATENT OFFICE.

LESTER E. SMITH, OF COTTON PLANT, ARKANSAS, ASSIGNOR TO EUREKA MANUFACTURING AND SALES COMPANY, INC., OF FORT SMITH, ARKANSAS, A CORPORATION OF ARKANSAS.

SAD-IRON.

1,188,213.

Specification of Letters Patent. Patented June 20, 1916.

Application filed August 19, 1914. Serial No. 857,589.

To all whom it may concern:

Be it known that I, LESTER E. SMITH, a citizen of the United States, residing at Cotton Plant, in the county of Woodruff and 5 State of Arkansas, have invented new and useful Improvements in Sad-Irons, of which the following is a specification.

The invention relates to sad-irons and more particularly to that class of sad-irons 10 known as self-heating sad irons.

The invention contemplates, among other features, the provision of a sad-iron embodying various improvements over a patent 15 on a sad-iron granted to me July 15, 1913, No. 1067557.

A still further embodiment of the invention resides in the provision of deflecting plates arranged within the body of the sad-iron and which can be removed for the purpose of replacing them by new ones in the 20 event that they should become broken or worn out.

In the further disclosure of the invention reference is to be had to the accompanying 25 drawings, constituting a part of this specification, in which similar characters of reference denote corresponding parts in all the views, and in which:

Figure 1 is a side elevation of the sad-iron; Fig. 2 is a vertical longitudinal sectional view taken through the body of the iron, the tank and adjacent parts being shown in side elevation; Fig. 3 is a plan view of the body of the iron, with the burner 30 and tank removed; Fig. 4 is a vertical transverse sectional view taken through the body of the iron, as shown in Fig. 3; Fig. 5 is a vertical transverse sectional view taken on the line 5—5 in Fig. 3; Fig. 6 is a perspective view of the burner and tank, showing the member for seating the burner within the body of the iron.

Referring more particularly to the views, I disclose a sad-iron 10 consisting of a body 45 11 having a flat face 12. The body 11 provides a heating chamber 13 and is adapted to receive a suitable cover 14 carrying a handle 15, the said cover having a forwardly extending pin 16 adapted to pass through 50 an aperture 17 in the front end of the body 11 in order that the cover can be more readily positioned upon the body, while swingingly mounted upon the top of the cover by means of a bolt that passes through its central portion is an arm the extremities of

which are adapted to move into engagement with slots 22 formed in posts 21 that are in turn formed integral with the body 11. From this arrangement it will be seen that when the pin 16 is inserted into the aperture 17 and the arms swung to a position to insert the extremities thereof into the slots 22 the cover will be held against movement. A series of relatively spaced uprights 18 project upwardly from the side walls of the body 11 and the cover is adapted to repose thereon, thus forming slots 19, between the uprights, and through which air can readily pass, the slots being further provided for the escape of any superfluous heat.

A burner tube 25 is adapted to lie within the body 11 and has threaded connection with a substantially circular supporting plate 26, the said burner tube being preferably provided with a series of slots 27 for the escape of gas and at which point the gas is ignited. Supported upon the plate 26 and projecting forwardly therefrom, immediately above the burner tube 25, is a generator tube 28. The supporting plate 26 has rigid therewith a pipe 29 supporting a tank 30 adapted to contain gasoline, the said pipe 29 communicating with one end of the generator tube 28. Similarly, a second pipe 31 is rigid with the supporting plate 26 and projects rearwardly therefrom, the said second pipe having communication with the other end of the generator tube 28 and carrying a suitable needle valve 32, slightly spaced from the inner or open end of the burner tube 25 and having an opening 33 adjacent thereto so that when gas is generated in the generator tube 28, upon opening the valve 32, the gas will pass into the burner tube 25 and be mixed with air at the point 35 where it enters the burner tube.

A rear wall 34 is formed within the body 11, a distance from the rear tapered end of the body and slightly behind the posts 21 having connection with the cover 14 for 40 the body, the said rear wall being provided with a central groove 35 and together with the walls of the body forming a seat 36 for the supporting plate 26.

The cover 14 carries a suitable heat resisting shield plate 37 on its under side at a point below the openings 19 so as to allow currents of air of relatively low degree to pass over the upper surface of the shield for carrying away the heat that would pass 45 50 55 60 65 70 75 80 85 90 95 100 105 110

to the under surface of the cover. It will be apparent that the valve and tank are arranged exteriorly of the body 11 and in order to substantially close the rear end of the body a depending flange 38 is formed on the rear end of the cover 14 and projects over the rear face of the supporting plate 26, thus not only facilitating the proper positioning of the supporting plate but also 10 preventing the flame from the burner tube or the heat produced by the flame from unduly heating the exterior of the tank 30 and which is preferably nickle plated or otherwise suitably finished to present a neat appearance.

As mentioned heretofore, the body of the sad-iron is adapted to contain deflecting plates for deflecting the flame at the burner and aiding in distributing the heat within 20 the body. These deflecting plates are indicated by the numeral 39 and are preferably supported within the body upon suitable posts 40 formed integrally with the body adjacent the side walls thereof, suitable 25 screws 41 being passed through the ends of the deflecting plates and into the posts 40, thus rigidly supporting the deflecting plates in horizontal position within the body and on both sides of the burner tube so that the 30 heat of the flame thereof will be evenly distributed throughout the body of the sad-iron. The deflecting plates 39 are preferably made of cast iron or the like and if they should become burned out can be readily 35 removed by simply removing the screws 41 and entirely removing the deflecting plates from the body and replacing the same by new ones.

From the foregoing description it will be 40 apparent that my sad-iron as described presents an article which will effectively accom-

plish the purpose for which it is designed; embodies various improvements over the patent on a sad-iron granted to me July 15, 1913 and bearing the number 1,067,557; that by providing the deflecting plates the heat from the flame of the burner tube will be more evenly distributed throughout the body of the iron and particularly exert itself against the flat face of the body; that the cover will be more securely held in locked position upon the body 11 of the sad-iron and that the burner and generator tubes as well as the tank supplying the vapor to the burner tube will be rigidly supported by the 50 plate 26 and which will be substantially held in rigid position on the body of the iron by arranging the same between the rear end of the body and the rear wall 34 provided for this purpose.

Having thus described my invention, I claim:

A sad iron comprising a hollow body, having a rear wall, a cover for said body and formed with a depending flange, there being oppositely disposed openings in said body where said cover engages the body, a shield plate detachably supported by said cover interiorly of said body at a point below the openings, and heating means supported on said rear wall and including a plate engaging the front surface of said flange and the rear surface of the said rear wall for preventing accidental movement of said means within said body.

In testimony whereof I affix my signature in presence of two witnesses.

LESTER E. SMITH.
